Primary Examiner—Holly Baynham*Attorney, Agent, or Firm*—Charles E. Yocum; Dennis A. Dearing; John D. Del Ponti[57] **CLAIM**

The ornamental design for a handle for vegetation cutter, as shown in the drawings.

DESCRIPTION

FIG. 1 is a right side perspective view of a preferred embodiment of a handle for a vegetation cutter in accordance with the present invention;

FIG. 2 is a bottom view of the handle of FIG. 1;

FIG. 3 is a top view of the handle of FIG. 1;

FIG. 4 is a rear view of the handle of FIG. 1;

FIG. 5 is a front view of the handle shown in FIG. 1;

FIG. 6 is a right side view of the handle shown in FIG. 1;

FIG. 7 is a left side view of the handle of FIG. 1;

FIG. 8 is a perspective view of the right side of a handle for a vegetation cutter in accordance with an alternative preferred embodiment of the present invention;

FIG. 9 is a bottom view of the handle of FIG. 8;

FIG. 10 is a top view of the handle of FIG. 8;

FIG. 11 is a rear view of the handle of FIG. 8;

FIG. 12 is a front view of the handle of FIG. 8;
FIG. 13 is a right view of the handle of FIG. 8; and,
FIG. 14 is a left view of the handle of FIG. 8.
